Dracon Industries, Chatsworth, Calif.

Filed Apr. 2, 1971, Ser. No. 130,877

Term of patent 14 years

Int. Cl. D10—99

U.S. Cl. D52—6 A

FIG. 1 is a perspective view of a magnetic supported template, showing my new design;

FIG. 2 is another perspective view thereof;

FIG. 3 is another perspective view thereof in another position;

FIG. 4 is a front elevation view thereof;

FIG. 5 is a rear elevation view thereof;

FIG. 6 is a plan view thereof; and

FIG. 7 is an increased scale end-elevation view thereof.

The views in FIGS. 2—6, inclusive, are fragmented for ease of illustration.

I claim:

The ornamental design for a magnetic supported template, substantially as shown and described.
